UNITED STATES PATENT OFFICE.

FRANK TAYLOR, OF ROCHESTER, NEW YORK.

DESIGN FOR A SCALE.

SPECIFICATION forming part of Design No. 30,938, dated June 6, 1899.

Application filed March 18, 1898. Serial No. 674,388. Term of patent 7 years.

To all whom it may concern:

Be it known that I, FRANK TAYLOR, a citizen of the United States, and a resident of Rochester, in the county of Monroe and State 5 of New York, have invented and produced a certain new and original Design for a Scale, of which the following is a specification.

This invention relates to a design for a scale for thermometers and other measuring 10 instruments; and it consists in the new and original scale, substantially as herein shown and described.

In the drawings, *a a* is the imaginary medial line of the graduated portion of the scale. *b b* 15 are sets of equal numbers of parallel lines indicating the smaller graduations upon said scale, and *c c* are lines indicating the limits of the greater graduations of said scale, dividing the sets of lines *b b* from each other.

20 The lines *b b* are parallel to each other and to the lines *c c*. The respective lines are

drawn at right angles to the medial line running between *a a*, and the sets of lines *b b* alternate on each side of said imaginary line. Vertical lines *d d* are arranged at the outer 25 ends of the sets of lines *b b*, and said lines *c c* are drawn from one line *d* to the corresponding line *d* upon the other side of the scale. The line *c* also extends slightly beyond the lower end of one of the lines *d*, with which it 30 is joined, and each line *c* is made somewhat broader or heavier than the lines *b*.

The leading feature of this design is the scale having the graduation-pattern consisting of the graduation-lines *b b*, *c c*, and *d*. 35

What I claim is—

The design for a scale herein shown and described.

FRANK TAYLOR.
